UNITED STATES PATENT OFFICE.

NEWTON W. LYON, OF IOWA CITY, IOWA.

SHOCK-HANDLING APPARATUS.

992,892.

Specification of Letters Patent. Patented May 23, 1911.

Application filed March 8, 1910. Serial No. 548,006.

To all whom it may concern:

Be it known that I, NEWTON W. LYON, a citizen of the United States, residing at Iowa City, in the county of Johnson and State of Iowa, have invented a new and useful Shock-Handling Apparatus, of which the following is a specification.

This invention relates to a shock handling apparatus and it consists in the novel construction and arrangement of its parts as hereinafter shown and described.

The object of the invention is to provide a simple and effective means for contracting the base portion of a shock as it stands in vertical position and for tilting the shock into a horizontal position and holding the base portion thereof contracted while a binder is applied thereto.

Thus it consists of means for tilting the shock into a horizontal position or it may be swung over upon its side upon a truck or other vehicle preparatory to transportation.

A further object of the invention is to include in the apparatus means for elevating and moving the shock in order that it may be deposited or stored at any desired point.

With the above object in view the shock handling apparatus includes a suspended track upon which is mounted a carriage having a locking device adapted to engage a keeper provided at one end of said track. A draft cable is operatively mounted with relation to the track and the carriage and is also connected with a frame adapted to be applied to the side of the shock and the said frame and the draft cable together with auxiliary cables form a means for contracting the base of the shock as indicated.

In the accompanying drawings,—Figure 1 is a perspective view of the apparatus. Fig. 2 is a side elevation of a shock with the frame applied thereto. Fig. 3 is a plan view of the frame applied to a shock. Fig. 4 is a side elevation of a modified form of frame. Fig. 5 is a top plan view of a portion of the frame showing a serrated cleat applied thereto. Fig. 6 is an elevation of the apparatus showing a modified form of frame applied to the shock which is in upright position. Fig. 7 is an elevation of a portion of the apparatus illustrating the parts in the act of contracting the base of a shock and tilting the same. Fig. 8 is a sectional view of a portion of the carrier of the apparatus. Fig. 9 is a side elevation of

the carriage forming a part of the carrier of the apparatus. Fig. 10 is a transverse sectional view through the track and carriage of the carrier. Fig. 11 is a plan view of a portion of the locking mechanism of the carriage.

In the assemblage of parts as illustrated in Figs. 1 and 6 of the drawings, the shock handling apparatus includes a platform 1 upon which is mounted a superstructure or frame 2. A track 3 is suspended from the frame 2 in the usual manner and is located above the platform 1. The platform 1 and the frame 2 may be the structure of a slide, sled or vehicle and one end of the track 3 projects beyond the end of the platform 1 for the purpose of raising the shock clear of the platform. The frame 2 includes an elevated beam 4 which lies transversely under the inner portion of the track 3. A carriage 5 is arranged to move along the track 3 and the said carriage with its component parts together with the said track form the carrier of the apparatus.

In the form of shock contracting frame as illustrated in Figs. 2, 3 and 7 of the drawings the said frame includes a bar 6 which is mounted at its end upon legs 7. The end portions of the said legs which are connected with the bar 6 converge toward each other. A cable 8 is secured at one end to the bar 6 at the point 9 thence passes around a sheave 10 carried by a block 11 and the said block 11 is attached to a cable 90 section 12. From the sheave 10 the cable 8 passes back to the bar 6 and through the same and around a sheave 13 journaled on the outer side thereof. From the sheave 13 the cable 8 passes around a sheave 14 also located upon the outer side of the bar 6, then through the said bar and around a sheave 15 journaled in a block 16 which in turn is attached to a cable section 17. The cable sections 12 and 17 are adapted to be adjustably tied together as at 18. From the sheave 15 the cable 8 is passed back to the bar 6 and through the same and around a sheave 19 which is journaled upon the outer side thereof. From the sheave 19 the said cable 8 passes around a sheave 20 also journaled upon the outer side of the bar 6 and is directed toward the periphery of the sheave 20 by means of a guide 21 of usual pattern. At a point between the sheaves 19 and 20 a cable clutch 20' of usual pattern is located upon the bar 6. This clutch is

adapted to engage the cable 8 and prevent backward movement of the said cable until the clutch is released.

As illustrated in Fig. 5 of the drawings, 5 the bar 6 is provided upon its inner side with a serrated cleat 22.

From the above description it will be seen that when the cable sections 12 and 17 have been adjusted with relation to each 10 other and tied as at 18 and the bar 6 placed against the side of the shock 23 and the cable 8 is drawn the blocks 11 and 16 are drawn toward the bar 6, the base of the shock 23 is contracted, and when the base 15 of the shock ceases to contract and draft is continued to be applied to the cable 8 the shock 23 may be tilted as indicated in dotted lines in Fig. 7 over upon the platform of a load vehicle 24. During such tilting movement 20 the legs 7 serve as fulcrums for the shock, and thus during the tilting of the shock the stalks thereof are not pushed longitudinally out of proper relation to each other. It is understood that the shock as 25 it stands upon the ground is provided with the usual binder 25 in the vicinity of its upper end. Prior to the contraction of the shock at the base a binder 26 may be placed across the apparatus as shown in Figs. 2 30 and 6 so as to retain the shock in contracted condition after the sections 12 and 17 have been released. After the binder 26 has been applied to the shock 23 and the same has been thrown over upon its side as 35 illustrated in Fig. 1 of the drawings, the shock may be engaged by a hay fork of the harpoon type or tongs, as indicated at 27 in Fig. 1 of the drawings. Or any other means may be employed for engaging the 40 shock while in such position.

In the form of tilting frame as illustrated in Fig. 4 of the drawings, a supplemental bar 28 is attached to the upper ends of the legs 7 and the said bar is parallel with the 45 bar 6 and is provided with a sheave 29 around which the cable 8 passes after passing around the sheave 20. This form of tilting frame is desirable when the shocks are wanted to be contracted close to the base 50 and yet be tilted over and upon a low vehicle. In the form of frame as illustrated in Fig. 6, the bar 6 with its pulleys only is employed and the legs 7 are eliminated. This form of the frame is used to lift the 55 shock direct from a normal position to the carrier by making use of the cable 47 explained hereinafter as an extension to the cable 8. After adjusting the cable sections 12 and 17 draw the cable 8 out as far as possible by hand on account of the upward angle of the draft cable 47 as shown in the illustration (see Fig. 6). This preliminary contraction of the shock is retained by the clutch 20'. The shock will be further contracted from the weight of the shock on the

lifting cable 47 and by said cable raised against a bolt 42 (to be described hereinafter) and thence forward as hereinafter described. The above mentioned frame or device may also be used to contract the shock 70 and tilt it over and upon a hay slide or low vehicle.

The carriage 5 which forms a component part of the carrier consists of a frame 30 to which are journaled wheels 31 which in 75 turn travel upon the upper side of the track 3. The frame 30 is provided at a point below the track 3 with a jaw 32 and an arm 33 is pivoted to the lower portion of the frame 30 and is provided with a jaw 34 80 which is located below the jaw 32. Said arm 33 is connected with an arm extension 33'. The jaw 34 is provided at one side with a flange or lug 35 which projects beyond the side of the jaw 32. A shaft 36 is journaled in the jaw 32 and an eccentric 37 is mounted upon the said shaft 36 and is located above the flange or lug 35 of the jaw 34. A sector 38 is fixed to the end portion of the shaft 36 and forms a crank whereby the 90 said shaft may be turned upon its axis. A sheave 39 is journaled upon the arm extension 33' and the forward portion of the arm 33' is pointed as at 40 and is provided with a shoulder 41 located behind the pointed extremity 40 thereof. A bolt 42 is slidably mounted in a perforation provided in the pointed end portion 40 of the arm extension 33' and a guide 43 is located at the lower end of the bolt 42. A keeper 44 is 100 fixed to the under side of the track 3 and is provided with an inclined side 45 which is located in the path of movement of the pointed end 40 of the arm extension 33'. A latch 46 is pivotally mounted in the keeper 105 44 and when the pointed end 40 of the arm extension 33' is in engagement with the inclined side 45 of the keeper 44 the free end of the said latch 46 will lie behind the shoulder 41 of the arm extension 33' and over the upper end of the bolt 42. When the tongs 27 or other similar shock engaging means is employed one end of the cable 47 is secured to the eye 48 upon the frame 30, then passes down and engages the shock-engaging device 27 and passes up through the guides 43 and over the wheel 39 and between the jaws 32 and 34. The cable then extends along the track 3 and passes around a pulley 49 journaled upon the beam 4 and from thence passes around a pulley 50 supported at the rear portion of the frame 2 and thence around a pulley 51 supported at the lower forward portion of the frame 2 and from the said pulley may be attached to 120 draft animals or a winding drum as desired. Thus it will be seen that as the cable 47 is drawn longitudinally through the jaws 32 and 34 while the forward end of the arm 33 is in engagement with the inclined side 130

45 of the keeper 44 the shock 23 will be elevated toward the carriage 5. When the said shock or its securing devices come in contact with the plate 43 the bolt 42 is
 5 moved vertically and the upper end thereof pushes the free end of the latch 46 from behind the shoulder 41 and the weight of the shock will swing the arm 33 down and the pointed extremity 40 of the said arm will
 10 move away from the inclined side 45 of the keeper 44. As the arm extension 33' swings as indicated the jaw 34 moves toward the jaw 32 and the cable 47 is clamped between the said jaws. As the cable continues to
 15 move longitudinally the carriage 5 is drawn along the track 3 toward the rear end of the frame 2. When the carriage has arrived at a desired point along the track 3, an operative pulls the rope 50' which is attached
 20 to the sector 38 and thus the said sector is swung, which in turn will partially rotate the shaft 36 which carries the periphery of the eccentric 37 down upon the flange 35 of the jaw 34 and thus the said jaw 34 is moved
 25 away from the jaw 32 and the cable 47 is liberated. At the same time the cable 47 is permitted to come to a state of rest and then as the said cable 47 is slackened the shock is lowered in position upon the platform 1.
 30 Having described the invention what I claim as new and desire to secure by Letters Patent is:—

1. In a shock handling apparatus, a shock compressor comprising a tilting frame made up of parallel bars, legs attached at their upper portions to the said bars and converging toward each other at their upper ends, sheaves mounted upon the lower bar, a sheave mounted upon the upper bar, a
 35 draft cable connected at one end with the lower bar and operatively engaging the sheave mounted thereon and passing over the sheave upon the upper bar, and a cable section having a sheave engaged by the
 40 draft cable, the cable section adapted to be
 45

applied to the opposite side of a shock from the said frame.

2. In a shock handling apparatus, a shock compressor comprising a bar having upon its inner face a serrated cleat, sheaves mounted upon the bar, a draft cable connected at one end with the bar and operatively engaging the sheaves thereon, and a cable section having a sheave operatively engaged by the
 50 said draft cable.

3. A shock handling apparatus including shock compressing means, a binder adapted to be applied to the shock when in compressed condition, a frame, a track suspended from said frame, a carriage mounted for movement along the frame, a keeper attached to the track, a fixed jaw mounted upon the carriage, an arm pivoted upon the carriage and having a jaw adapted to cooperate with the first said jaw, a shaft
 60 journaled upon the carriage, an eccentric mounted upon said shaft, means for turning said shaft upon its axis, the movable jaw having a lug located in the path of movement of the periphery of said eccentric, a
 65 wheel journaled upon said arm, said arm having a shoulder, a latch pivoted in the keeper and adapted to engage the shoulder, a bolt slidably mounted upon the arm, a
 70 guide carried by the bolt, the upper end of the bolt being located under the latch when the said arm is in engagement with the keeper, a cable attached at one end to the carriage, a shock-engaging means carried by the cable, said cable passing over the
 75 wheel journaled upon the arm thence between the jaws of the carriage, and means for guiding the cable along the track.

In testimony that I claim the foregoing as my own, I have hereto affixed my signature
 80 in the presence of two witnesses.

NEWTON W. LYON.
